UNITED STATES PATENT OFFICE.

KIRK K. WRIGHT, OF BUFFALO, NEW YORK, ASSIGNOR TO R. G. WRIGHT & CO., OF BUFFALO, NEW YORK.

CENTRIFUGAL PUMP.

Application filed January 6, 1922. Serial No. 527,813.

To all whom it may concern:

Be it known that I, KIRK K. WRIGHT, a citizen of the United States, residing at Buffalo, in the county of Erie and State of New York, have invented a new and useful Improvement in Centrifugal Pumps, of which the following is a specification.

This invention relates to centrifugal pumps.

10 Pumps of this kind as heretofore made have had certain objections when used in connection with milk or similar liquids, the principal objection being that a centrifugal pump seems to have a certain churning effect on the milk and to cause an objectionable amount of frothing or foaming. Pumps of this kind have also been hard to clean.

15 The objects of this invention are to provide a pump of this kind which is so constructed as to materially reduce the frothing or churning action of the pump, also to so construct pumps of this kind as to facilitate the cleaning thereof; also to produce a pump which may easily be set or adjusted to various positions; also to improve the construction of pumps of this kind in other respects hereinafter specified.

20 In the accompanying drawings;

25 Fig. 1 is a side elevation of a centrifugal pump embodying the invention,

Fig. 2 is a side elevation thereof with the cover for the pump housing removed therefrom,

Fig. 3 is a face view of the cover for the pump housing,

Fig. 4 is a longitudinal central sectional elevation thereof on an enlarged scale,

Fig. 5 is a sectional elevation thereof on line 5—5, Figure 4,

Fig. 6 is a transverse sectional elevation thereof on line 6—6, Figure 1,

Fig. 7 is a fragmentary detail view on an enlarged scale showing the connection between the end of the shaft and the rotor or impeller, and

Fig. 8 is a section thereof on line 8—8, Figure 4.

The centrifugal pump may be mounted on any suitable base or frame, that shown including a base plate A which may be secured to a floor or other support and which has upwardly extending bearing standards a and a' on which a shaft B is suitably

journalled. The base also has an upwardly extending transverse supporting plate or member C to which the housing D of the pump is secured, the plate C being reinforced by means of arms c connecting the bearing standard a' with the plate C. The shaft B may be driven by any suitable means, pulleys b and b' being provided in the construction shown which are arranged between the two bearings a and a'. All of these parts may be of any other desired construction.

In centrifugal pumps as heretofore made the pump housing has generally been eccentric with reference to the rotor of the pump and the ends of the rotor or impeller blades arranged at a considerable distance from the inner surface of the housing. I have found that the objectionable churning action and frothing in pumps as heretofore made is due to the fact that the outer ends of the impeller blades pass through the milk in such a way as to cause a violent agitation at the ends of these blades. This action is prevented in my improved construction in which the main portion of the pump housing D is substantially concentric with the axis of the rotor and only a comparatively small portion of the housing adjacent to the discharge pipe is eccentric and in which the impeller blades are so formed

35 that the ends thereof extend into close proximity to the inner surface of the pump housing. Consequently violent agitation of the milk takes place only in the comparatively small eccentric portion of the housing and this agitation is not sufficient to produce objectionable frothing or churning. In the particular embodiment of the invention shown in the drawings the pump housing includes a substantially flat side or radial wall d which may be secured to the plate C of the base by means of screws d' or the like, and a circumferential wall including a portion d² which is concentric with the axis 40 of the shaft B and a portion d³ which is eccentric with reference to the shaft B and terminates in a discharge pipe d⁴. This pipe

45 may be connected by any suitable coupling d⁵ or the like with a discharge pipe.

50 The circumferential wall of the pump housing is substantially cylindrical in form and is not transversely concaved as is the usual centrifugal housing. This feature is

particularly desirable in cleaning the pump since the cylindrical circumferential wall forms no pocket or recess in which either milk or washing water may collect, so that 5 the pump, even if carelessly washed, will not retain any material which might contaminate the milk.

E represents the rotor or impeller of the pump which has a plurality of blades e 10 which in the construction shown extend spirally from a hub portion e', the hub portion of the rotor being suitably secured on the end of the shaft B. The outer ends e² of the impeller blades are formed to extend into close proximity to the concentric portion d² of the housing of the pump and these ends are preferably formed to present a considerable area, which is concentric with the axis of the propeller. Consequently 15 the clearance between the ends of the blades and the housing is very small, and, owing to this small clearance and the extended area of the ends e², very little liquid can flow through the space between the ends of the blades and the housing, so that the frothing or churning action is reduced to a minimum in the concentric part of the pump. Furthermore, by making these blades spiral 20 in form and by providing relatively large surfaces on the outer ends e² of the blades, the rear ends of the blades terminate in relatively sharp edges e³, which in passing through a body of liquid, cause practically no eddies or whirling of liquid at these 25 portions of the blades, but cause the liquid to be discharged from the spaces between the blades with a minimum loss of efficiency due to eddies, and with a minimum amount of frothing or churning action. Each of 30 these blades is preferably provided with a longitudinal central recess or depression e⁴ which assists in pumping the milk without excessive frothing thereof.

The rotor may be connected with the shaft 45 B in any suitable or desired manner, this connection being preferably such as to permit the rotor to be readily removed from and attached to the end of the shaft. In the construction shown for this purpose the hub e' 50 of the rotor is provided with a projecting hub portion f through which a pin F extends, the pin being suitably secured to the portion f of the hub. The end of the shaft B is provided with a longitudinal slot f' 55 into which the pin F may enter. The inner end of the slot f' is enlarged radially with reference to the axis of the shaft as indicated at f² to permit the pin to enter into the enlargements and thereby prevent the hub 60 from moving lengthwise with reference to the shaft. By means of this construction the rotor can be easily placed on the shaft by placing the hub on the shaft in such a manner that the pin F enters into the slot f' 65 and then giving the rotor a slight turn so

that the pin enters into the enlargements f² which prevent the endwise movement of the rotor. The removal of the rotor can be easily effected by slightly turning the 70 same so that the pin may pass through the slot f'. The rotor is prevented from being disconnected from the end of the shaft during the operation of the pump by the walls of the housing.

The housing of the pump is provided with a cover or closure G having a substantially radial portion g which extends into close proximity to the adjacent side faces of the rotor and an intermediate or axial inlet portion g' which is hollow and through 75 which the fluid to be pumped may enter into the housing. The axial portion of the cover is threaded as indicated at g² so that an inlet pipe g³ may readily be connected with the cover by means of a coupling g⁴ or the like. A cover of any other suitable construction may be provided.

In order to make the cover readily removable from the pump housing, the housing cover is provided with a plurality of ears or projections h having slots h' into 80 which thumb screws or bolts H may extend. These screws have a threaded engagement with lugs h² preferably formed with the housing D and the outer ends of the screws are provided with handle portions or wings h³ by means of which the screws may easily be turned. In order to remove the cover from the housing each of the screws H is given a partial turn whereupon the housing cover may be turned to cause the wings h to move out of engagement with the 85 screws so that the cover may be readily removed from the housing. Any other means for securing the cover to the housing may be provided.

By mounting a part of the housing of the pump on the plate C as shown, the pump housing may readily be adjusted to different positions with reference to the base of the pump, this being accomplished by placing the screws d' at equal distances apart so that the threaded holes in the pump housing may be placed into registration with any of the holes in the plate C. In the construction shown, four fastening screws are provided and consequently the pump housing may be secured in four different positions. In Figure 6 two of these positions are indicated, the full lines showing a position of the housing whereby the discharge pipe is arranged at the bottom of the housing, whereas the dotted lines indicate the discharge pipe arranged at the upper portion of the pump. Similarly the pump may discharge at either side thereof. By means of this arrangement the pump can be readily adapted to cooperate with a pasteurizer or other apparatus with which the same is to be used, and in installing the pump no ma- 100

chine work is necessary to place the pump housing in any one of the several positions in which the same may be secured.

I claim as my invention:

5 1. In a centrifugal pump, the combination of a housing open at one side and having a discharge passage formed integral therewith on the peripheral portion thereof, a rotor shaft extending through said housing 10 into the same, a supporting member having an upwardly extending portion to which said housing is secured, a bearing for said rotor shaft supported by said upwardly extending portion, a removable side wall having 15 an inlet for the liquid to be pumped and adapted to be secured to and removed from the open side of said housing without disturbing said discharge outlet, and means for securing said housing on said upwardly 20 extending portion in different positions about the axis of said shaft, to arrange said discharge outlet in different relations with reference to said supporting member.

2. In a centrifugal pump, the combination 25 of a drive shaft, a housing having a circumferential wall, the greater portion of which is concentric with said shaft, and a rotor having a plurality of blades, the outer ends of which form surfaces of extended area and which are formed concentric 30 with said shaft and extend into as close proximity with said concentric portions of said housing as is possible without producing friction, said outer ends and the rear 35 faces of said blades meeting at an acute angle at the rear outer portions of said blades.

3. In a centrifugal pump, the combination 40 of a housing having a radial wall and a circumferential wall provided with a discharge outlet, a rotor shaft extending through said radial wall, a supporting member to which said housing may be secured and having an upwardly extending portion, a bearing 45 for said rotor shaft on said upwardly extending portion, and means for securing said radial wall to the upwardly extending portion of said supporting member in different positions to arrange said discharge 50 outlet in different relations with reference to said supporting member.

4. In a centrifugal pump, the combination 55 of a housing having a radial wall and a circumferential wall formed integral therewith, a rotor shaft extending through said radial wall, a supporting member having a part to which said radial wall may be secured, securing devices for holding said housing in different relations to said supporting member, and a cover for said housing which is provided with an axial inlet 60 for the liquid.

5. In a centrifugal pump, the combination 65 of a housing, a drive shaft extending into

said housing, a rotor mounted in said housing on the end of said shaft, the end of said shaft having a longitudinally extending slot, the inner portion of which is enlarged, a pin secured to said rotor and adapted to enter into said longitudinal slot 70 in said shaft and to be held in said enlarged portion of said slot against endwise movement relatively to the shaft, and a part on said housing which is spaced adjacent to said rotor and prevents the rotor 75 from moving in a direction to enable said pin to move out of said slot.

6. In a centrifugal pump, the combination 80 of a drive shaft, a rotor having a hub portion which is removably mounted on the end of said shaft, the end of said shaft being provided with a longitudinal slot, the inner end of which is enlarged, and a pin extending through the hub portion of said rotor and adapted to enter said slot 85 when the shaft enters lengthwise into said hub, said pin being movable into said enlargements of said slots by turning said shaft and hub portion relatively to each other, and being held against endwise movement relatively to said shaft by said enlargements, the torque transmitted to said rotor serving to hold said pin in said enlargements of said slot.

7. In a centrifugal pump, the combination 90 of a housing having a radial wall and a circumferential wall, a drive shaft extending through said radial wall and having a slot in the outer end thereof, a rotor detachably mounted on said shaft and having a part 95 cooperating with said slot, and a removable radial wall mounted on said housing and having an inlet for the liquid to be pumped, said removable wall cooperating with said rotor to hold said part of said rotor in operative relation to said slot.

8. In a centrifugal pump, the combination 100 of a housing which is open at one side thereof and closed at the other side, a drive shaft extending into said housing through said closed side thereof, a removable side wall adapted to close the open side of said housing and having an inlet for the liquid to be pumped, a rotor mounted on said shaft, 110 cooperating parts on said rotor and shaft for holding said rotor against turning relatively to said shaft and which permit said rotor to be moved freely lengthwise of said shaft out of engagement therewith, said removable side wall serving to hold said cooperating parts on said rotor and shaft in operative relation to each other when the rotor is idle, and means on said rotor and shaft which cooperate only when power is transmitted to the rotor to hold the same 120 out of contact with said wall.
